UNITED STATES PATENT OFFICE.

CHARLES E. GODLEY, OF DETROIT, MICHIGAN, ASSIGNOR, BY MESNE ASSIGNMENTS, TO EDMUNDS & JONES CORPORATION, OF NEW YORK, N. Y., A CORPORATION OF NEW YORK.

OIL-LAMP BURNER.

1,199,543.

Specification of Letters Patent. Patented Sept. 26, 1916.

Application filed January 19, 1916. Serial No. 72,898.

To all whom it may concern:
Be it known that I, CHARLES E. GODLEY, a citizen of the United States, and residing at Detroit, in the county of Wayne and State 5 of Michigan, have invented a new and Improved Oil-Lamp Burner, of which the following is a specification.

This invention relates to burners for oil-lamps and particularly to means for centering the wick-tube relative to the shell or skirting of the burner, and its object is to provide means for holding the upper end of the wick-tube in proper central position relative to the flame opening in this shell or 15 skirting.

This invention consists in a small transverse frame secured to the upper end of the wick-tube of the burner, of an oil-lamp and so formed as to engage the upper part of the 20 burner shell or casting adjacent the flame opening so as to hold the wick in alignment with this opening.

In the accompanying drawing, Figure 1 is an elevation of a lamp provided with a 25 burner equipped with the improved centering device for the wick-tube, the burner being shown in section. Fig. 2 is an elevation of the base and wick-tube of a burner, the shell being shown in section. Fig. 3 is a 30 plan of the wick-tube.

Similar reference characters refer to like parts throughout the several views.

The lamp body 1 shown in the drawing supports a head or top 2, a door 3, a lens 4 and a lining 5. The font 6 has a top 7 provided with a flange 8 that engages with a flange 9 on the body. A burner is mounted on the font and consists of a body 11, a perforated flaring flange 12, a wick-tube 13, a 40 wick-shaft 14, a knob 15 on the end of the shaft, a wheel 16 extending into the wick-tube, and a shell or skirting consisting of the upper portion 17 provided with a hemispherical top formed with the flame-opening 18, and the lower flange 19. This burner is 45 preferably equipped with a washer 20 of yielding material, such as leather, and may be held down on the font when the parts are assembled by means of the resilient fingers 50 23 mounted on the lining 5.

The body and shell may be secured together by means of inwardly extending projections or shoulders 22 so positioned that the edge of the flaring flange 12 can be

forced past these projections and be held in 55 position thereby.

None of the parts thus far described form any part of the present invention.

When the upper end of the wick-tube is not central with the flame-opening, the flame 60 of the lamp is uneven and smoky, often tailing at one corner of the wick, and usually of less than maximum brightness, because a sufficient amount of air cannot reach all 65 parts of the flame. The best effect is produced when a sufficient amount of air flows to the flame from all sides at about the same speed, and to insure this a small frame consisting of a plate 25 is secured to the upper end of the wick tube and is provided with 70 pairs of fingers 26 having upwardly extending flanges 27 that engage the inner surface of the shell 17 as shown in the drawings. This plate or flame spreader 25 and the fingers are spaced a sufficient distance from the shell 17 to permit a free flow of air to the 75 sides of the flame while the fingers 26 are spaced apart sufficiently to permit sufficient air to reach the edges of the flame. The up-turned flanges 27 serve to stiffen the fingers 26 and to engage the hemispherical top of the shell. It will be seen that so long as this small frame is in position, the upper end of the wick-tube is necessarily in alignment 80 with the flame opening.

I claim:

1. In an oil-burner, the combination of a body and a wick-tube projecting therefrom, a shell mounted upon the burner body and having an upper hemispherical portion provided with a flame-opening, a plate secured to the upper end of the wick-tube, and pairs of fingers extending from said plate and in opposite directions from said wick-tube into engagement with said shell. 95

2. In an oil-burner, the combination of a body and a wick-tube projecting therefrom, a shell mounted upon the burner body and having an upper hemispherical portion provided with a flame-opening, a plate secured to the upper end of the wick-tube, and pairs of fingers extending from said plate and in opposite directions from said wick-tube into engagement with said shell at the ends of 100 said flame-opening.

3. In an oil-burner for lamps, the combination of a body, a shell or skirting mounted thereon and having its upper portion formed 105

with a transverse slot constituting a flame-opening, a wick-tube extending through said burner body and having its upper end at approximately the height of the lower ends of the flame-opening, and a narrow frame secured to the upper end of said wick-tube and having pairs of fingers extending from its ends into engagement with said shell, the

frame being spaced a sufficient distance from said shell and the fingers being spaced a sufficient distance apart to permit air to flow freely to the said flame-opening.

In testimony whereof I sign this specification.

CHARLES E. GODLEY.
